UNITED STATES PATENT OFFICE.

JAMES T. MINYARD, OF MULBERRY, ARKANSAS.

SUPPORT FOR VEHICLE-SHAFTS.

No. 879,188.

Specification of Letters Patent.

Patented Feb. 18, 1908.

Application filed April 11, 1907. Serial No. 367,717.

To all whom it may concern:

Be it known that I, JAMES T. MINYARD, a citizen of the United States, residing at Mulberry, in the county of Crawford and State of 5 Arkansas, have invented certain new and useful Improvements in Supports for Vehicle-Shafts, of which the following is a specification.

My invention is a support for vehicle 10 shafts and is designed to hold the thills or shafts up in a perpendicular, or nearly perpendicular position so they will be out of the way from being trampled on or run over, or broken by other such means, and that the 15 animal may be conveniently put in position and taken away from the vehicle when the shafts are thus supported at such angles.

In the accompanying drawings, Figure 1, is a front end view of a buggy, provided with 20 my improved shaft or thill support in position, holding the thills up, the swinging arm being under the cross-beam of the thills. Fig. 2, is a face view of my invention. Fig. 3, is a vertical sectional view. Fig. 4, is a 25 perspective view and Fig. 5, is perspective detail views of the several parts, except the bolt, washers and nuts.

My invention, referring to the drawings, as attached to the front end of a vehicle, is described as follows:—

The numeral 1, designates the main bar which is provided at its upper end with a square enlargement 2, horizontal perforation 3, and stop pin 4, and near its center with an 35 oblong rectangular opening 5, and near its lower end with a horizontal perforation 6.

An elbow-shaped bar 7, is provided near its vertical end with an oblong rectangular opening 8, which corresponds to the oblong 40 rectangular opening 5. Its horizontal part is provided with a square opening 9, said horizontal part terminating in a threaded neck 10.

The numeral 11, represents the swinging 45 arm, provided at its end with a flattened part 12; the said arm turns at a right angle, forming a wrist 13, which is provided with a shoulder 14, said wrist terminating in a threaded bolt 15. Fitting over the threaded 50 bolt 15, and against the face of the shoulder 14, is rigidly secured a washer 16, provided with a stop shoulder 17.

My invention is applied as follows:—The main bar 1, is applied to the front edges of 55 the upper half of the buggy spring, and to the bolster. The elbow-shaped bar 7, is then

applied to the rear edges thereof, the threaded neck 10, passing forwardly through the perforation 6, of the bar 1, and secured by a nut 18. The lower end of the bolt and the nut 19, which holds the bolster to the spring passes through the square opening 9, of the elbow-shaped bar 7; then a bolt 20, is passed from the rear through the rectangular opening in the elbow plate 7, thence over the top 60 of the bolster, thence through the oblong rectangular opening 5, of the main bar 1, and secured by a washer 21, and nut 22.

The purpose of having the openings 5 and 8, oblong, and vertically constructed, and 65 having the threaded ends of the neck 10, and bolt 20, long, is to have this part of the device so that it may be adjusted to buggies where the spring and bolster are of different sizes. The bolt 15, of the wrist 13, is then passed 70 rearwardly through the perforation 3, in the main bar 1, until the face of the washer comes against the enlargement 2, and in such position that the stop shoulder 17, will rest against the left side of the stop pin 4, thus 75 causing the swinging arm 11, to stand to the left at an angle from the main bar 1, of about 10 degrees, so that when the pressure against 80 the cross bar of the thills is relieved by pushing one of the thills back a little, the arm drops down of its own weight and thus the thills are, so to speak, automatically relieved. The arm is pivoted in place by a washer 23, 85 and a nut 24; thus placed in position it is 90 ready for use.

Although I have specifically described the combination, construction and arrangement of the several parts of my invention I do not confine myself particularly to such specific combination, construction and arrangement, 95 as I claim the right to make such changes and modifications therein as may clearly fall within the scope of my invention, and which may be resorted to without departing from the spirit, or sacrificing any of my rights 100 therein.

Having described my invention, what I claim as new and desire to secure by Letters Patent, is,

The combination of the main bar 1, provided at its upper end with a square enlargement 2, a perforation 3 and stop pin 4, and near its middle a longitudinal rectangular opening 5, and near its lower end with a perforation 6; elbow-shaped bar 7, provided near its upper end with an oblong rectangular opening 8 in its vertical part, and with a 105 110

square opening 9, in its horizontal part, said horizontal part terminating in a threaded neck 10; a swinging arm 11, provided with a wrist 13, at right angles to said arm; a shoulder 14, on said wrist, said wrist terminating in a threaded bolt 15; a washer 16, rigidly secured to said shoulder and around said bolt provided with a stop shoulder 17, said bolt 15, pivoted and secured in said opening 10 3, by washer 23, and nut 24, said stop shoulder adapted to rest against said stop pin 4;

parts 1 and 7 adapted to be secured around the upper spring and bolster of a vehicle by means of bolts and nuts, substantially as shown and described and for the purposes 15 set forth.

In testimony whereof I affix my signature, in presence of two witnesses.

JAMES T. MINYARD.
